A. L. T. Corporation, Dover, N. J., a corporation of
Delaware

Application May 13, 1957, Serial No. 46,116

Term of patent 14 years

(Cl. D26—14)

FIG. 1

FIG. 2

Figure 1 is a top plan view of an automatic loudspeaking telephone, showing my new design;

Figure 2 is a side elevational view, the opposite side having substantially the same appearance;

Figure 3 is a rear elevational view, to a reduced scale;

Figure 4 is a front elevational view, to a reduced scale; and

Figure 5 is a bottom plan view thereof, to a reduced scale.

The broken line showing of a hand set and dialing wheel in Figure 1 is for illustrative purposes only.

I claim:

The ornamental design for an automatic loudspeaking telephone, as shown and described.
